UNITED STATES PATENT OFFICE.

ARTHUR HALE, OF NEW YORK, N. Y.

HEAD-COVERING PROVIDED WITH BAND.

1,051,326.

Specification of Letters Patent. Patented Jan. 21, 1913.

Application filed October 21, 1911. Serial No. 656,068.

To all whom it may concern:

Be it known that I, ARTHUR HALE, a citizen of the United States, residing at New York, in the county of New York and State 5 of New York, have invented certain new and useful Improvements in Head-Coverings Provided with Bands; and I do hereby declare the following to be a full, clear, and exact description of the invention, such 10 as will enable others skilled in the art to which it appertains to make and use the same.

This invention relates to washable head gear, especially to hats and caps, and has 15 for its object to produce an article of this character which will permit the stiffening members to be readily withdrawn, when the fabric out of which the head covering is made can be washed, and then the said stiff- 20 ening members can readily be re-inserted.

To these ends the invention consists in the novel details of construction and combinations of parts more fully hereinafter disclosed and particularly pointed out in 25 the claims.

Referring to the accompanying drawings forming a part of this specification in which like numerals designate like parts in all the views:—Figure 1 is a sectional view of a 30 banded cap or other head covering made in accordance with my invention; Fig. 2 is a diagrammatic plan view in section of the band portion of the cap shown in Fig. 1; Fig. 3 is an enlarged detail sectional view 35 taken on the line 3—3 of Fig. 1, and looking in the direction of the arrows; Fig. 4 is a perspective view of the stiffening member removed from the cap; and Fig. 5 is a perspective view on a reduced scale of a modified form of stiffening member, which is especially useful in connection with caps 40 having vizors.

1 represents a cap or other head covering made of any suitable material, but preferably 45 composed of a washable fabric. The band portion of said cap is composed of an outer wall 2 and an inner wall 3 made of a suitable fabric stitched or otherwise secured together along their edges 18, as illustrated, 50 to form a pocket 4. In the pocket 4 is an endless band 5 also made of a washable fabric, and which band need not necessarily be removed from the said pocket 4. The said band 5 is provided with a button, or other 55 fastening means, 6 which is adapted to pass through a slit or button-hole 7 in the stiffen-

ing member or band 8, which is adapted to be inserted into and removed from the pocket 4, as will now be disclosed. That is to say, the inner wall 3 is provided with a 60 slit or other opening 9 through which the stiffening band 8 may enter, and in order to readily insert the said band into the pocket 4 and to remove it therefrom, I preferably move the button 6 to such a position that it comes opposite the opening 9, when the said button is inserted through the slit or button-hole 7 in the stiffening member 8, whereupon by pulling on the endless band 5, the said button-hole end of 70 the member 8 is drawn into the pocket 4 and a continual pulling on the endless band 5 will thereupon draw the entire member 8 into the pocket 4 and substantially into the position shown in Fig. 2, whereupon it 75 serves as a stiffener for the band portion of the cap 1, and, of course, may be worn until the cap becomes soiled. The said stiffening member 8 is also preferably provided with a strip of flexible material 10 to serve as a 80 handle portion, or means for the ready withdrawal of the member 8 when it is desired to wash the cap. This member 10 is preferably secured to the member 8 at a distance from the extreme end thereof, as indicated 85 in Fig. 4, and is adapted to fold around and over said end, as indicated in Fig. 3, when the said member is in operative position in the pocket 4. By thus securing the handle portion 10 a slight distance away 90 from the extreme end 11 of the member 8, the said end 11 is slightly curled over when withdrawing it from the pocket 4, and thereupon its withdrawal is facilitated.

Accordingly when it is desired to wash the 95 cap the strip 10 is seized by the fingers, the extreme end 11 is withdrawn through the opening or slit 9 and the entire stiffening member 8 gradually pulled out of the pocket 4, the endless band 5 in the meantime traveling around the said pocket, until the said button 6 again comes opposite the opening 9, whereupon the member 8 is disengaged from the band 5 and the cap is ready for washing. After the cap is washed, dried and ironed, if 100 desired, the button 6 is again inserted through the slit or button-hole 7, the member 8 re-inserted into the pocket 4 and the cap is again ready for use.

In the modified form shown in Fig. 5 a 110 stiffening member of the shape of a vizor for a cap is shown, and the same is readily

insertible through an opening leading to the vizor such as is fully disclosed in my co-pending application, Serial No. 652,357, filed October 2, 1911, entitled Head coverings. In said application, however, the stiffening member for the vizor there illustrated is not provided with the flexible strip or handle portion which is illustrated in this application. Therefore, according to the 10 present invention I provide the stiffening member 15 suitable for vizors with a flexible strip such as 10, and preferably secure the same to the underside of said stiffening member at a slight distance from the extreme tip 16 of said member.

It is obvious that those skilled in the art may vary the details of construction as well as the arrangement of parts without departing from the spirit of my invention, therefore I do not wish to be limited to the above disclosure except as may be required by the 20 claims.

What I claim is:—

1. A head covering provided with a band 25 portion comprising inner and outer walls secured together along their top and bottom edges and provided with an open mouth pocket into which a stiffening member may be readily inserted and from which it may 30 be readily withdrawn, substantially as described.

2. A head covering provided with a band

portion comprising closed inner and outer walls constituting a pocket provided with an open mouth; and a stiffening member located in said pocket capable of ready insertion into and withdrawal from said pocket, substantially as described. 35

3. A head covering provided with a band portion comprising inner and outer walls 40 constituting a pocket provided with an open mouth; and means within said open mouth pocket for drawing a stiffening member thereinto.

4. A head covering provided with an open 45 mouth pocket; and shiftable means confined in said pocket and provided with means for detachably engaging a stiffening member to draw the latter within said pocket.

5. A head covering provided with a band 50 portion comprising closed inner and outer walls constituting a pocket with an open mouth; an endless band in said pocket; a stiffening member located in said pocket capable of ready insertion into and withdrawal from said pocket; and means for detachably securing said stiffening member to said endless band, substantially as described. 55

In testimony whereof, I affix my signature, in presence of two witnesses.

ARTHUR HALE.
